ELECTRIC DISCHARGE LAMP LUMINAIRE

Arthur A. Brainerd, Erwinna, Pa.

Application October 26, 1953, Serial No. 388,103

6 Claims. (Cl. 240—25)

This invention relates to a luminaire, and more specifically concerns a luminaire of the electric discharge type which is particularly advantageous for lighting streets, highways and the like.

It is well known that the efficiency of electric discharge lamps is considerably higher under optimum temperature conditions than the efficiency of incandescent lamps of the same wattage. Electric discharge lamps have, therefore, gone into extensive use in factories, office buildings and the like.

In my prior U. S. Patent No. 2,610,289, granted September 9, 1952, I disclose and claim an electric discharge lamp luminaire which has capacity for efficient operation at various temperatures falling generally within the range of natural ambient temperature conditions. Like the luminaire of the aforementioned issued patent, the luminaire constructed in accordance with this invention is enclosed and is electrically heated, and has capacity for efficient operation under natural ambient conditions.

It is an object of this invention to provide an electric discharge lamp luminaire which is adapted to be mounted adjacent to a street or highway to direct a flood of illumination at an angle across the highway and at an elevation slightly above but immediately adjacent to the highway level.

Still another object of this invention is to create an electric discharge lamp luminaire of an improved, non-glare design.

Still another object is to create a luminaire having a plurality of enclosed light sources together with reflector means which is adapted to focus and direct the light at an acute angle across a street, highway or the like.

Still another object of this invention is to create a luminaire of simple and practical construction which has an improved lighting efficiency as compared to other luminaires and is sufficiently rugged for permanent installation adjacent a street, highway or the like.

Other objects and advantages of this invention, including the simplicity and economy of the same, will further appear hereinafter and in the drawings, whereof:

Fig. 1 represents a plan view of a divided highway, showing a plurality of electric discharge lamp luminaires positioned adjacent thereto;

Fig. 2 represents a side elevation of an electric discharge lamp luminaire constituting one specific embodiment of this invention;

Fig. 3 represents a plan view of the luminaire taken as indicated by the lines and arrows III—III which appear in Fig. 2, with certain parts broken away in order to illustrate further important details;

Fig. 4 represents a vertical sectional view taken as indicated by the lines and arrows IV—IV which appear in Fig. 3, the central portion of the luminaire being broken away;

Figs. 5 and 6 represent sectional views taken as indicated by the lines and arrows V—V and VI—VI respectively, which appear in Fig. 4;

Fig. 7 represents a sectional view showing the mounting

2

means for one of the reflector members, taken as indicated by the lines and arrows VII—VII which appear in Fig. 5; and

Fig. 8 represents a view in perspective of the electric discharge lamp luminaire shown in the preceding figures.

Turning now to the specific embodiment of the invention selected for illustration in the drawings, Fig. 1 shows a divided highway having a pair of spaced apart highway strips 10, 11 with a central strip 12 therebetween.

10 Located at uniformly spaced positions along the central strip 12, along two parallel lines extending adjacent to the respective strips 10, 11, are a plurality of electric discharge lamp luminaires 13. The luminaires 13 are enclosed and have reflectors 14 which are constructed and arranged to direct light rays across the highway strips 10, 11 at an acute angle with respect to the edge of the highway. The relatively heavy lines (a) in Fig. 1 illustrate the fact that the majority of the light from the luminaires 13 is directed along a more or less definite 15 zone, while the relatively light lines (b) in Fig. 1 represent light beams of relatively minor intensity which border the major zone. From Fig. 1 it will be appreciated that the majority of the light from the luminaires 13 is directed generally in the direction of travel of the 20 vehicles on the highway which is indicated by the arrows (c), and at an acute angle with respect thereto. Accordingly, the vehicles on the highways are flooded with bright light without creating any noticeable glare in the eyes of the drivers, either directly or by reflection from the 25 rear view mirrors, the highway being incidentally illuminated by spill light. The luminaire is supported at such an angle that the bottom of the light beam passes across the highway above and substantially parallel to its surface. The light, which is thus directed horizontally close 30 to the highway surface, gives maximum visibility in fog or other adverse weather conditions. This is an important and advantageous feature of this invention.

Turning now to Fig. 2 of the drawings, the construction of the luminaires is brought out in more particular 35 detail. The number 9 represents a base pipe which is imbedded in the central strip 12. Disposed inside the base pipe 9 are a pair of lead wires 8, 8 comprising sources of high voltage electricity for energizing the luminaire. Formed integrally with the base pipe 9 at its upper end 40 is a flange 15, slotted at 16 (Fig. 6) for the reception of a plurality of bolts 17. The bolts 17 extend through openings in an upper flange 20 which is formed integrally with a vertical post 21. The luminaire 13 is affixed to the post 21 by a split sleeve 22 near the top of the luminaire, and by a base 23 upon which the luminaire is supported. From Fig. 2 of the drawings it will be apparent that the lead wires 8, 8 extend upwardly into the post 21 and that they extend outwardly through the post 21 and enter the luminaire 13 through an insulator 45 28.

Turning now to Figs. 3 and 4 of the drawings, it will be apparent that the base 23 includes a base plate 29 which carries a pair of depending guard cups 24, 24 comprising housings for a pair of sockets 25, 25. An inverted U-tube 26 extends vertically upwardly from the sockets 25, 25 and has a plurality of prongs 27 which are securely engaged within the sockets 25, 25.

Extending upwardly from the base plate 29 is a cylindrical elongated enclosure 30, in which the U-tube 26 is 55 disposed. A stiffener plate 31 extends transversely across the top of the enclosure 30, having an annular groove in which the upper edge of enclosure 30 is fitted. Fixed to the top of plate 31 is a dome 32, which includes a removable light dispersive upper dome portion 33. The stiffener plate 31 is slotted at 34 directly above the upper end of U-tube 26 providing an opening through which 60 light rays are directed upwardly into the dome.

Turning now to Figs. 5 and 7 of the drawings, the reflector plate 14 is fixed to the base plate 29 by means of a plurality of angle irons 41 (Fig. 7). The reflector plate 14 comprises a substantially flat sheet or plate of metal or other material, bent in a single plane forming a plurality of curved reflective surfaces as illustrated in Fig. 5 of the drawings. It will be apparent that the reflector plate 14 shown in Fig. 5 consists of two substantially parabolic portions 42, 43, which intersect one another along the straight line 44. It will be appreciated that the curved portion 42 coacts with the leg 45 of U-tube 26, while the curved portion 43 coacts with the leg 46 of U-tube 26. Each curved portion 42, 43 has a curvature which decreases with increasing distance from the axis of its corresponding U-tube leg, whereby light from the legs is beamed in the same general direction. Each beam has the general form of a rectangular parallelepiped. Preferably the curved reflector plates 42, 43, in horizontal section, are segments of parabolas having parallel axes, and the legs 45, 46 are preferably located at the spaced focal points of the parabolas.

Adjustably supported on the base 29, inside the enclosure 30, are a plurality of louvers 47. The louvers 47 have capacity to swing about vertically arranged pivots 48 within the enclosure. It will be observed that the louvers 47 are located adjacent to one edge of the reflector plate 14. The louvers 47 serve to deflect light traveling directly from the vertical leg 45, since they are opaque, and also serve to deflect light reflected from the parabolic portion 43 having the vertical leg 46 as a source. This is an important and advantageous feature of the invention, as will further appear.

From Fig. 5 it will be apparent that the curved intersecting reflector plates 42, 43 extend substantially completely across the space within the enclosure 30, dividing the enclosure into two sections 50, 51. The section 50 is illuminated and is bounded by the reflective faces of the curved reflector plates. The space 51 is located rearwardly of the curved reflector plates, and is not necessarily illuminated. The wires 8, 8 lead into the rearwardly located enclosure space 51. Mounted in the space 51 is a reactor 52. One wire 8 leads directly to one of the U-tube sockets 25, while the other wire 8 is connected to the end of a coil 53; this wire is also by-passed through a thermostat 54 for connection into an intermediate portion of the coil 53. The arrangement and wiring of the thermostat and reactor appear in further detail in my aforementioned issued U. S. Patent No. 2,610,289, and constitute no part of this invention.

Turning now to Fig. 8 of the drawings, it will be appreciated that the enclosure for the electric discharge lamp preferably consists of a metal or other opaque body portion 30 having an opening into which a light transmitting window 61 is sealed. Window 61 consists of glass, plastic or the like having good visible light transmission characteristics and a low thermal conductivity when used in cold climates. However, for use in hot climates the window 61 preferably has high thermal conductivity. In the embodiment of the invention illustrated in Figs. 5 and 8, the sealing means between the window and the body portion 30 comprises a continuous rubber or other resilient strip 62, which has opposed slots formed to receive the opposed edges of the members 30, 61. It will be appreciated that it is important to form a good seal between the members 30, 61 since heat developed by the lamp 26, reactor 52, when retained in the enclosure, materially improves the efficiency of operation of the electric discharge lamp in cold weather.

It will also be appreciated from Fig. 8 that two spaced sight members 63, 63 are mounted on the top of the enclosure adjacent to the dome member 32. The sight members are aligned with the principal path of the light beam, and are accordingly located in a fixed position with respect to the curved reflector plates 42, 43, parallel to the axes of the parabolic reflectors.

While the light beams produced by the apparatus shown in the drawings are preferably substantially parallel to one another, it will be appreciated that the relative arrangement of the lamp and reflectors may be modified in accordance with this invention to provide beams of other types. For example, the reflectors may be hinged together as illustrated at 44a in Figs. 5 and 8 for relative swinging movement about the vertical line 44 along which they intersect, to produce convergent or divergent beams. For this purpose the angle irons 41 shown in Fig. 7 may be provided with slots 70 on their bases and other slots 71 (Fig. 8) may be provided on the reflectors 42, 43. Moreover, utilizing this structure, the reflectors may be moved bodily toward and away from the light sources. Other modifications will be readily apparent and may be made to provide optimum beaming for the particular conditions existing.

In the operation of the electric discharge lamp luminaire, the device is adjusted to the desired angle with respect to the street or highway by loosening the bolts 17 and revolving the luminaire with respect to the flange 15 and post 9. The luminaire may be quickly positioned at any predetermined angle by sighting along the sight members 63, 63. The bolts 17 are then tightened to secure the luminaire in the desired angular position with respect to the street or highway. It will be appreciated that the light beam is substantially restricted to a path extending at an acute angle with respect to the movement of the vehicles on the street or highway, and that the louvers 47, because of their construction and arrangement can readily be adjusted with respect to the curved reflectors. This greatly reduces or completely eliminates direct glare in a direction substantially parallel to the path of movement of vehicles along the street or highway. Moreover, the adjustable character of the louvers coacts with the adjustable character of the base. Accordingly, the luminaire is not only a highly efficient source of bright, soft light which is free of glare, but is also constructed to confine the light to a relatively low beam disposed immediately above and parallel to the road surface and extending at an acute angle with respect to the direction of vehicular travel thereon.

The construction of the plate 31 and removable dome 33 in combination with the slot 34 in the plate 31 utilizes efficiently the light from the bend of U-tube 26. Moreover, it provides a convenient means for removing and replacing the U-tube 26. This is accomplished by lifting off the dome 33, reaching through slot 34 to grasp the closed bend of the U-tube, and withdrawing the U-tube through slot 34.

It will be appreciated that the reactor 53 and thermostat 54 as shown in the drawings are located at the lowest convenient available space within the enclosure. This is important. While this arrangement is adequate for service in warm climates, it is even preferable to locate the reactor wholly below the horizontal plane tangential to the bottom of U-tube 26 when the luminaire is to be used in colder climates. Moreover, for cold weather service the thermostat 54 should be located below the reactor and in the best position for response to the ambient temperature. Furthermore, when the reactor is mounted below the base plate 29, the base plate 29 should be provided with large openings permitting heated air to flow upwardly into the space occupied by the U-tube 26.

While this invention has been described with reference to one specific embodiment adapted for a specific purpose, it will be appreciated that various changes may be made in the form of the device and in the manner of its application, and that the invention is applicable to a variety of types of luminaires other than the particular one here selected for illustration. For example, parts may be reversed, equivalent elements may be substituted, and certain features of the invention may be utilized independently of the use of other features, all within

the spirit and scope of the invention as defined in the appended claims.

Having thus described the invention, I claim:

1. An electric discharge lamp luminaire comprising an enclosure, a U-tube lamp having a bend at the upper end thereof in said enclosure, said enclosure having a brace plate located above the bend of the U-tube, said brace plate being slotted above said bend, and a removable lighting dome located above the slot and supported by said brace plate to receive light from the bend of the U-tube, said light passing through said slot, said dome being removable and said slot being of a size to permit withdrawal of the U-tube through said slot.

2. An electric discharge lamp luminaire comprising an enclosure having a light transmitting window therein, an electric discharge lamp disposed in said enclosure, said lamp including a plurality of generally upright elongated lamp members, a generally upright reflector spaced from said lamp members including a pair of reflective generally parabolic surfaces which intersect each other and which surfaces terminate along the line of intersection, said generally parabolic surfaces having generally parallel axes along which the light is directed and said surfaces having focal points which are spaced from one another measured in the direction of said axes whereby one of said generally parabolic surfaces is arranged forwardly of the other generally parabolic surface measured along the path of the light beam, the remote outer ends of both said parabolic surfaces extending forwardly well beyond a line joining said focal points, said lamp members and the corresponding parabolic surfaces being so arranged that light from either lamp member may impinge directly on either of the extensions of said parabolic surfaces, the intervening space between said extensions being devoid of any light obstruction or barrier, said reflective surfaces being constructed and arranged to reflect the light forming a light beam directed through said window, and a plurality of opaque louvers in said enclosure extending upwardly adjacent to an edge of said window and bounding one edge of said light beam.

3. An electric discharge lamp luminaire comprising an enclosure, a generally upright electric discharge lamp extending substantially from the bottom to the top of said enclosure, said enclosure having brace means located above the upper end of said lamp, said brace means having an opening above said lamp, and a lighting dome located above said opening and supported by said brace means to receive light from the upper portion of said lamp, said light passing through said opening, said dome being removable and said opening being of a size to permit withdrawal of said lamp through said opening.

4. An electric discharge lamp luminaire comprising a substantially upright elongated enclosure, a dome disposed on top of said enclosure, an inverted U-tube electric discharge lamp having legs disposed substantially upright in said enclosure, the closed end of the U being substantially adjacent said dome in position to direct light into said dome, and a reflector spaced below said dome adjacent said U-tube legs, said reflector including

a pair of reflective generally parabolic surfaces which intersect each other and which surfaces terminate along the line of intersection, said generally parabolic surfaces having generally parallel axes along which the light is directed and said surfaces having focal points which are spaced from one another measured in the direction of said axes whereby one of said generally parabolic surfaces is arranged forwardly of the other generally parabolic surface measured along the path of the light beam.

5. The luminaire defined in claim 4 wherein a brace plate extends transversely of the upper portion of said enclosure above the U-tube below the dome, and wherein the brace plate has a light-transmitting opening intermediate the U-tube and the dome for permitting light to pass from said U-tube to said dome.

6. An electric discharge lamp luminaire comprising an enclosure having a light transmitting window therein, an electric discharge lamp disposed in said enclosure, said lamp including a plurality of generally upright elongated lamp members, a generally upright reflector spaced from said lamp members including a pair of reflective generally parabolic surfaces which intersect each other and which surfaces terminate along the line of intersection, said generally parabolic surfaces having generally parallel axes along which the light is directed and said surfaces having focal points which are spaced from one another measured in the direction of said axes whereby one of said generally parabolic surfaces is arranged forwardly of the other generally parabolic surface measured along the path of the light beam, the remote outer ends of both said parabolic surfaces extending forwardly well beyond a line joining said focal points, said lamp members and the corresponding parabolic surfaces being so arranged that light from either lamp member may impinge directly on either of the extensions of said parabolic surfaces, the intervening space between said extensions being devoid of any light obstruction or barrier, and said reflective surfaces being constructed and arranged to reflect the light forming a light beam directed through said window.
